PORT, CONNECTICUT, A CORPORATION OF CONNECTICUT.

MEANS FOR LOCKING TOOL-SHANKS AND FERRULES TO HANDLES.

1,253,379.

Specification of Letters Patent.

Patented Jan. 15, 1918.

Application filed August 11, 1917. Serial No. 185,683.

To all whom it may concern:

Be it known that we, WILLIS F. HOBBS and CHARLES W. GIBBS, citizens of the United States, residing at Bridgeport, county 5 of Fairfield, State of Connecticut, have invented an Improvement in Means for Locking Tool-Shanks and Ferrules to Handles, of which the following is a specification.

This invention relates to the manufacture 10 of tools having shanks seated in handles, and the object of the invention is to provide suitable and inexpensive means for locking the shank to the handle and preventing looseness or separation, for locking a round 15 shank against turning in the handle and for locking the ferrule to the handle no matter how much the wood may shrink, and to accomplish these results without drilling either tool shank or ferrule.

20 With these and other objects in view we have devised the novel locking means for tool shanks and ferrules which we will now describe referring to the accompanying drawing forming a part of this specification 25 and using reference characters to indicate the several parts.

Figure 1 is a perspective view, partly in section, illustrating the attachment to each other of a tool shank, ferrule and handle in 30 accordance with our novel invention;

Fig. 2 a perspective view showing the parts disassembled and also showing a variant form of locking key;

Figs. 3 and 4 are longitudinal sectional 35 views showing the use of other forms of locking keys, and

Fig. 5 is a section on the line 5—5 in Fig. 4 looking in the direction of the arrows.

10 denotes a tool shank which is simply 40 round stock having a tool formed at one end thereof, 11 the tenon of a wood handle and 12 a ferrule. The essential feature of the invention is that we lock the tool shank against longitudinal movement relatively to 45 the handle, lock it against rotation in the handle and lock the ferrule to the handle by means of a key or keys engaging the three parts and rigidly secured in place by the driving on of the ferrule. The handle 50 is provided with the usual longitudinal bore 13 and the tenon is provided with a transverse recess 14, which may extend only to the bore or may extend entirely through the tenon, intersecting the bore. The tool shank

is provided with a recess or recesses 15 which are formed by punching out metal on one side or on opposite sides as preferred. This punching operation is relatively inexpensive and does away with the necessity for drilling which is an expensive operation. When the 55 parts are assembled the recesses in the tool shank and handle tenon are in alinement. In each pair of corresponding recesses we place a key 16, the inner end of which engages the tool shank and the outer end of 60 which projects slightly above the face of the tenon. The special form of key used is not of the essence of the invention. We find in practice that flat ended plug keys such as shown in Fig. 1, and at the right in Fig. 2, 70 answer the purpose admirably and are much cheaper to produce than other forms. If preferred, however, the plug keys may be made as shown at the left in Fig. 2, that is with their outer ends chamfered off and provided with central recesses 17, leaving circular engaging ribs as points of contact, or if preferred the plug keys may be made as shown in Fig. 3, that is with teats 18 at their outer ends to be engaged by the wall of the 75 ferrule.

In Figs. 4 and 5, we have shown a form of the invention in which the key 19 is in the form of a segment of a disk and engages a corresponding transverse recess 20 in the 85 tenon and a similar recess 21 in the tool shank.

The operation of assembling will be readily understood from Fig. 2. The ferrule is placed over the tool shank, then the tool 90 shank is driven home in the handle, the recesses being placed in alinement with the recesses in the tenon, then the key or keys are placed in the corresponding recesses in the tenon and the tool shank, and then 95 the ferrule is driven to place over the tenon. As already explained the ends of the keys are left to project slightly beyond or outside the outer ends of the recesses in the tenon, so that when the ferrule is driven 100 home there will be a substantially permanent frictional engagement of the ferrule and the keys, by reason of the engagement of such projections with the ferrule and the relative slight difference in angle of the inner surface of the ferrule and the outer ends of the keys, and the inner ends of the keys will be 105 driven into rigid engagement with the re-

cesses in the tool shank. This leaves the ferrule, tool shank and handle rigidly locked to each other, so that there can be no endwise or rotary movement of the tool shank relatively to the handle and the ferrule remains locked to the key or keys even if the tenon shrinks away from the ferrule.

Having thus described our invention, we claim—

- 10 1. Means for attaching a tool shank, handle and ferrule to each other comprising a tool shank and handle tenon having corresponding recesses, a key in said recesses having its outer end projecting slightly out side the recess in the tenon and a ferrule driven to place over the tenon, the angle between the inner surface of the ferrule with respect to the outer end of the key being such that a substantially permanent frictional engagement between the inner surface of the ferrule and the outer end of the key is provided.
- 15 2. In combination, a tool shank having a

recess, a handle tenon having a recess in alinement therewith when the tool shank is 25 driven home, a key in said recesses projecting slightly outside the recess in the tenon and a ferrule driven home over the tenon, the angle of the inner surface of the ferrule with respect to the outer end of the key being such that the shank, tenon and ferrule are united by a substantially permanent frictional engagement.

3. The method of securing tool shanks, handle tenons and ferrules to each other, 35 which consists in providing recesses in the shanks and tenons which correspond when the shanks are driven home, placing keys in said corresponding recesses and providing a substantially permanent frictional union between the parts by driving the ferrule home over the tenons.

In testimony whereof we affix our signatures.

WILLIS F. HOBBS.
CHARLES W. GIBBS.
